Des. 202,753
Patented Nov. 2, 1965

202,753

BARBECUE CART

Charles F. Wiedeman, Jr., 903 Oregon Trail,
Cincinnati, Ohio

Filed Aug. 3, 1964, Ser. No. 81,130

Term of patent 3½ years

(Cl. D81—10)

Des. 202,753

PAGE 2

FIG. 5

The predominant features of my design reside in those portions shown in full lines.

I claim:

The ornamental design for a barbecue cart, substantially as shown and described.
